(57) **CLAIM**

The ornamental design for a camera stand, as shown and described.

DESCRIPTION

The application file contains at least one drawing executed in color. Copies of this patent or patent application publication with color drawing(s) will be provided by the Office upon request and payment of the necessary fee.

FIG. 1 is a perspective view of a camera stand in one embodiment of the ornamental design;

FIG. 2 is a front view of the camera stand in FIG. 1;

FIG. 3 is a left view of the camera stand in FIG. 1;

FIG. 4 is a rear view of the camera stand in FIG. 1;

FIG. 5 is a right view of the camera stand in FIG. 1;

FIG. 6 is a top view of the camera stand in FIG. 1;

FIG. 7 is a bottom view of the camera stand in FIG. 1;

FIG. 8 is a perspective view of a camera stand in a second embodiment of the ornamental design, in which tonal variation is shown;

FIG. 9 is a front view of the camera stand in FIG. 8;

FIG. 10 is a left view of the camera stand in FIG. 8;

FIG. 11 is a rear view of the camera stand in FIG. 8;

FIG. 12 is a right view of the camera stand in FIG. 8;

FIG. 13 is a bottom view of the camera stand in FIG. 8;

FIG. 14 is a top view of the camera stand in FIG. 8;

FIG. 15 is a perspective view of a camera stand in a third embodiment of the ornamental design, in which tonal variation is shown;

FIG. 16 is a front view of the camera stand in FIG. 15;

FIG. 17 is a left view of the camera stand in FIG. 15;

FIG. 18 is a rear view of the camera stand in FIG. 15;

FIG. 19 is a right view of the camera stand in FIG. 15;

FIG. 20 is a bottom view of the camera stand in FIG. 15;

FIG. 21 is a top view of the camera stand in FIG. 15;

FIG. 22 is a perspective view of a camera stand in a fourth embodiment of the ornamental design, in which colour variation is shown;

FIG. 23 is a front view of the camera stand in FIG. 22;

FIG. 24 is a left view of the camera stand in FIG. 22;

FIG. 25 is a rear view of the camera stand in FIG. 22;

FIG. 26 is a right view of the camera stand in FIG. 22;

FIG. 27 is a bottom view of the camera stand in FIG. 22;

FIG. 28 is a top view of the camera stand in FIG. 22;

FIG. 29 is a perspective view of a camera stand in a fifth embodiment of the ornamental design, in which colour variation is shown;

(Continued)

FIG. 30 is a front view of the camera stand in FIG. 29;
 FIG. 31 is a left view of the camera stand in FIG. 29;
 FIG. 32 is a rear view of the camera stand in FIG. 29;
 FIG. 33 is a right view of the camera stand in FIG. 29;
 FIG. 34 is a bottom view of the camera stand in FIG. 29;
 and,
 FIG. 35 is a top view of the camera stand in FIG. 29.
 The broken lines in the drawings depict portions of the
 camera stand that form no part of the claimed design.
